CLAIM

The ornamental design for a foldable play tray, as shown and described.

DESCRIPTION

FIG. 1 is a perspective view of a foldable play tray showing our new design;

FIG. 2 is an enlarged front elevational view thereof;

FIG. 3 is a left side elevational view, the right side being a mirror image thereof;

FIG. 4 is a top plan view thereof;

FIG. 5 is a bottom plan view thereof;

FIG. 6 is a perspective view in extended position; and

FIG. 7 is a perspective view with the legs in folded condition and a writing surface attached to the top.
